UNITED STATES PATENT OFFICE.

ROBERT D. STRUBLE, OF PHILADELPHIA, PENNSYLVANIA, ASSIGNOR OF
ONE-HALF TO JOHN J. CAIN, OF PHILADELPHIA, PENNSYLVANIA.

RELEASE-HINGE.

SPECIFICATION forming part of Letters Patent No. 750,908, dated February 2, 1904.

Application filed October 13, 1903. Serial No. 176,893. (No model.)

To all whom it may concern:

Be it known that I, ROBERT D. STRUBLE, a citizen of the United States, residing at Philadelphia, in the county of Philadelphia and State 5 of Pennsylvania, have invented certain new and useful Improvements in Release-Hinges; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

This invention relates to new and useful improvements in movable release-hinges designed for use in connection with doors, adapting the same to be mounted upon hinges at either longitudinal edge thereof for convenience in having ready access from either edge 20 of the door.

More specifically, the invention comprises a novel construction of hinge comprising socket-plates adapted for attachment to the jamb or edge of an opening and in the provision of an eccentric member which is mounted upon the door and actuated by means of a knob whereby the tongue-carrying plates positioned adjacent to one or the other of the longitudinal edges of the door may be thrown 25 out of engagement with the socket member to allow the door to swing upon the hinges at the opposite longitudinal edges of the door.

The invention comprises, further, various details of construction and combinations and arrangements of parts, which will be hereinafter 30 fully described and then specifically defined in the appended claims.

My invention is illustrated in the accompanying drawings which, with the letters of 35 reference marked thereon, form a part of this application, and in which drawings—

Figure 1 is a view of a door equipped with my improved hinges. Fig. 2 is an enlarged detail view of one of the socket-plates. Fig. 45 3 is a view of one of the spring-actuated tongue-carrying hinge-plates. Fig. 4 is an enlarged detail view of the eccentric member

utilized to actuate the tongue-carrying plate as the knob is turned, and Fig. 5 is a detail view of a guide-plate mounted upon the door 50 and adapted to hold the tongue-carrying plate as it is moved sidewise by the eccentric member operated by the knob.

Reference now being had to the details of the drawings by letter, A designates one of 55 the hinge-plates, having two solid cylindrical bearing portions A' and A'', respectively, and intermediate said portions A' and A'' is a hollow cylindrical shell B, integral with the plate A and having an elongated recess B' opening 60 into the hollow cylindrical portion thereof. Said plate A is provided with apertures a, whereby the same may be secured to the jamb of a door or casing of any opening where the hinges are to be utilized. There are preferably 65 two of the plates A used upon ordinary doors, although more may be employed, if desired.

C designates a metallic bar which has two laterally-projecting portions C' at the ends 70 thereof, said projecting portions comprising tongues which are apertured at D to receive the cylindrical shell B and form bearings upon which the bars turn when fastened to a door. The length of each projection or tongue C' is 75 such as to allow the same to turn between the solid cylindrical portions A' and A''. A guide-plate E has one of its horizontal edges turned to form a flange E', while the opposite edge of the plate from that having the flange E' has 80 a shorter flange F, extending only partially across the edge of the plate. These plates are provided with screw-apertures e, whereby the same may be fastened securely to a door, adjacent to its top and bottom, and the flange extending the entire width of each edge of the plates is adapted to engage over the ends of the bars C, as shown clearly in Fig. 1 of the drawings, and form a guideway whereby said bar may have a side movement for the purpose of 85 throwing the tongues into or out of engagement with the cylindrical socket members B. The flange F upon each plate E is adapted to engage over the inner edge of each tongue,

as shown in the drawings, to further assist in guiding said bar in its movements.

At any suitable location along the longitudinal edges of the door are secured plates H, 5 which may be countersunk in the door or secured in the face thereof, as may be desired, and K designates a cam-shaped member having its convexed side mounted adjacent to the concaved outline of the recess in the outer 10 edge of the bar C, and L designates a knob which is swiveled to the plate H, being held in an aperture therein by the upsetting of the inner edge of the knob, while the shank portion of said knob is secured to said cam member and so arranged that the latter and knob will move together. Each bar C (there being one mounted adjacent to each margin of the door and of similar construction) is provided with a cam member and a knob adapted to 15 20 actuate the same and so arranged that when the knob is turned in either direction a portion of the convexed edge of the cam will bear against the adjacent concaved edge of the bar for the purpose of moving the same 25 sidewise, which movement will throw the tongues carried by the bar C out of engagement with the cylindrical socket members B, integral with the plates A, which latter are stationary. Springs M have ends fastened 30 to the rear edges of the bars C, while their other free ends are adapted to bear against a shoulder or some other part of the door, the purpose of which springs is to normally throw the bars C to their farthest outward throw, in 35 40 which positions the tongues carried by the bar C would engage the cylindrical socket members.

The operation of my improved hinges will be readily understood and is as follows: When it is desired to have one or the other of the edges of the door swing, the knob which is positioned adjacent to the swinging edge of the door is turned either in one direction or the other, which movement will throw the two 45 50 55 tongues upon the adjacent door C out of engagement with the socket members B, which will cause the door to swing upon the bar on the opposite edge of the door. When it is desired to have the other longitudinal edge of the door to swing, the knob upon the opposite edge is operated in a similar manner, as described.

By the provision of a hinge apparatus embodying the features of my invention a great 55 60 65 convenience is afforded in operating wardrobe or closet doors or upon other articles of furniture, as bookcases, &c., where it would be an inconvenience to have the door swing in but one direction, thus giving ready access 60 to locations behind one or the other longitudinal edge of the door.

While I have shown and described a particular construction of apparatus embodying

my hinge apparatus, it will be understood that I may make alterations in the detailed construction of the same, if desired, without in any way departing from the spirit of the invention.

Having thus fully described my invention, what I claim as new, and desire to secure by Letters Patent, is—

1. A releasing-hinge for doors comprising stationary hinge members, each provided with a hollow socket member and solid portions, spaced apart therefrom, a door, spring-actuated bars carried one at each longitudinal edge thereof, and having apertured tongues adapted to have hinged relation with said socket members, and means for throwing said tongues into and out of engagement with said socket members, as set forth.

2. A releasing-hinge comprising plates, each having a socket member and adapted to be secured to the jamb of a door, bearing members upon each plate, spaced apart from said socket member, a spring-actuated bar mounted adjacent to each longitudinal edge of the door and having apertured tongue projections adapted to have hinged relation with said socket members, a knob mounted adjacent to each longitudinal edge of the door, and a cam member rotated by said knob and adapted to bear against the edges of a bar to move the same sidewise to throw one or the other set of tongues out of engagement with said socket members, as set forth.

3. A releasing-hinge for doors comprising plates adapted for attachment to the jamb of a door and having a hollow socket member and solid bearing projections, spaced apart from the ends of said socket member, a spring-actuated bar mounted adjacent to each longitudinal edge of the door and having apertured tongue projections adapted to have hinged relation with said socket members, flanged guide-plates carried by the door and holding said bars thereto, a knob secured to the door adjacent to each of said bars, a cam fitted to rotate with said knob and adapted to bear against said bar for the purpose of moving the same sidewise to disengage the tongue projections from said socket members, as set forth.

4. In combination with a door, a releasing-hinge comprising a plate having a hollow socket member along one of its marginal edges, solid bearing members integral with said plates and spaced apart from said socket member, bars adapted to be mounted upon a door and having apertured tongue extensions, springs secured to the inner edges of said bars and bearing against a portion of the door and serving normally to hold said bars at their farthest outer limit, said apertured tongue extensions being adapted to be seated between said bearing extensions and have hinged connection with said socket member, a knob mounted

at each longitudinal edge of the door, a cam member fitted to said knob and having a convexed edge adapted to bear against the concaved edge of a recess in said bar, and flanged 5 plates secured to the door and adapted to engage and form guideways for the ends of the bars, as set forth.

In testimony whereof I hereunto affix my signature in presence of two witnesses.

ROBERT D. STRUBLE.
